UNITED STATES PATENT OFFICE.

ARTHUR P. STRONG, OF CHICAGO, ILLINOIS, ASSIGNOR TO GREEN ENGINEERING COMPANY, OF EAST CHICAGO, INDIANA, A CORPORATION OF ILLINOIS.

ASH HOPPER.

Application filed October 6, 1921. Serial No. 505,702.

To all whom it may concern:

Be it known that I, ARTHUR P. STRONG, a citizen of the United States, residing at Chicago, in the county of Cook and State 5 of Illinois, have invented new and useful Improvements in Ash Hoppers, of which the following is a specification.

This invention relates to metal hoppers or tanks for the collection and disposal of 10 ash or other disintegrated materials.

One object of my invention is to make the walls of the tank or hopper of supporting beams and metal plates and to secure the plates to the beams by bolts as distinguished 15 from hooking the plates over the beams or having their side edges engaged in channels in the beams.

A further object is to provide means for covering and protecting the inner ends of 20 the bolts from corrosion or abrasion from the material packed or stored in the tank or hopper.

The invention consists further in the matters hereinafter described and more particularly set forth in the appended claims.

In the accompanying drawings—

Fig. 1 is a side elevational view of a storage tank or hopper constructed in accordance with my invention;

30 Fig. 2 is an enlarged fragmentary inside view of a portion of one of the upright walls of said tank or hopper;

Fig. 3 is a vertical sectional view taken on line 3—3 of Fig. 2;

35 Fig. 4 is a horizontal sectional view taken on line 4—4 of Fig. 2;

Fig. 5 is an elevational view with parts in section of the structure shown in Fig. 4; and

40 Fig. 6 is a perspective view of one of the wall plates.

In the drawings, I have shown a storage tank or hopper of the type having upright side and end walls 1, 1 and a hopper bottom 2 provided with a gate controlled discharge opening, as customary in structures of this general kind. The tank or hopper is usually elevated or supported above the ground or platform, as the case may be, the distance 45 required to permit emptying of the hopper into a car or truck when moved under the same. As shown in Fig. 1, the structure includes a plurality of upright posts 3, 3 for this purpose. The upright side and end walls 1, 1 rest on and are connected with a

horizontal base frame 4 at the upper ends of the posts 3, as indicated in Fig. 1. The side and end walls 1 are made alike, so a description of one will answer for all.

Secured to the base frame 4 are a plurality of upright beams or members 5, 5. These are laterally spaced apart and, as shown in Fig. 4, are in the shape of I-beams. Said beams 5 extend upward the same distance and are all connected together at their 60 upper ends by a cross-member 6 at the top of the tank or hopper, as shown in Fig. 1.

The spaces between the upright beams 5, 5 are closed by metal plates 7, 7. These are arranged one above the other in each of the 70 vertical spaces and are located inside of the beams, as shown. The plates 7 are secured to the beams between which they extend by bolts 8, 8, these being at the upper edge of each plate only, in the form of structure shown 75 in the drawings. The bolts 8 extend through the plates and side flanges of the beams overlapped by the plates, and have their heads 9 inside of the plates, while their threaded outer ends extend outside of the beams and 80 in position to have the clamp nuts applied thereon.

As shown in Fig. 3, the upper edge or margin of one plate 7 is overlapped on the inside by the lower margin of the plate 85 thereabove. This closes the joints between such margins of the plates and prevents the material packed in the tank from leaking out between the plates. By having the overlapping inside, a downward shed is provided and avoids upwardly facing ledges for the material to accumulate or collect on. The side edges of the plates 7 either abut or are closely adjacent the like edges of the associated plates on opposite sides thereof 90 and these edges overlap the associated beams 5, 5 to prevent leakage between the beams and the plates.

Each plate, as shown in Fig. 5, is provided along one of its side edges with an integral, 100 inwardly offset portion or flange 10 in a plane parallel to the plane of the plate body. The flange 10, as shown in Fig. 5, has its upper end short of the upper edge of the plate, while its lower end extends to 105 the bottom edge of the plate and continues around the corner thereof to provide a recess or pocket 11. The flange 10 overlaps the side margin of the adjacent side plate 7 and closes the joint between the plates to 110

prevent an accumulation of material therein. The lower end of said flange 10 extends over and covers the heads 9, 9 of two bolts 8, 8, as shown in Fig. 4, these bolt heads being 5 in the pocket 11. The right-hand bolt 8, shown in Figs. 4 and 5, secures to the beam 5 the upper left-hand corner of the plate 7 immediately below said flange 10, and the bolt 8 which secures to said beam 5 the 10 upper right-hand corner of the plate 7 to the right of the plate with which the right-hand bolt is engaged. The flange 10 is provided with an inwardly extending horizontal rib 12 to close the pocket 11 from below 15 and prevent the material finding its way into and filling the pocket 11. The opposite lower corner of the plate 7 is cut out, as at 13 and 14. The former is larger to clear the left-hand bolt head 9, shown in Fig. 5, and its 20 edge 15 closes the adjacent side of the pocket 11, and the notch 14 seats on the rib 12, as shown in Fig. 5. Thus, the pocket is closed from the side as well as the bottom, and on the opposite side of the integral portion 25 between the plate body and the flange 10. The upper end of the flange 10, terminating short of the upper edge of the plate, accommodates the lower end of the flange 10 on the plate thereabove, as shown in Fig. 3.

30 All of the bolt heads 9 in the wall structure are located in pockets 11 and thus are shielded and protected from corrosion or abrasion from the material stored or packed in the hopper or tank. This is a marked 35 advantage, because the life of the bolts is prolonged by being free from abrasion as the tank is filled and emptied, and, shielded from corrosion, may be readily removed and replaced in making repairs to the tank.

40 Moreover, these features make possible the use of bolts for securing the plates to the supporting beams as the objection to corrosion and abrasion is overcome.

The hopper bottom 2 of the tank may 45 be constructed like the upright walls, or in a manner similar to that shown in either of the prior Patents Nos. 1,243,873, granted October 23, 1917, or 1,311,296, granted July 29, 1919 to myself and Herman A. Poppenhusen.

50 While I have shown and described herein in detail a hopper or tank constructed in accordance with my invention, it is of course to be understood that the details of construction and arrangement of parts may be variously changed and modified without departing from the spirit and scope of my invention.

I claim as my invention:

60 1. A wall, comprising plate supporting beams, plates arranged inside of said beams and closing the spaces between the same, and

bolts securing the plates to said beams, said plates having means extending over the inner ends of said bolts for protecting the same 65 from contact with the material packed against the inside of said wall.

2. A wall, comprising plate supporting beams, plates arranged inside of said beams and closing the spaces between the same, and 70 bolts securing the plates to said beams, the bolts of one plate having their inner ends overlapped and covered by the marginal portion of another plate for protecting the bolts 75 from contact with the material packed against the inside of said wall.

3. A wall, comprising plate supporting beams, plates extending across the spaces between said beams on the inside thereof, and bolts securing the plates to said beams, 80 each plate having an inwardly offset marginal portion overlapping the adjacent plate and extending over the bolts of the latter plate for protecting the inner ends of the same from contact with the material packed 85 against the inside of said wall.

4. A wall, comprising plate supporting beams, plates extending across the spaces between said beams on the inside thereof, and bolts securing the plates to said beams, each 90 plate having an inwardly offset marginal portion extending around one of the corners of said plate and overlapping the two adjacent plates for covering the bolts of the latter plates and protecting the same 95 from contact with the material packed against the inside of said wall.

5. An upright wall, comprising plate supporting beams, a plurality of plates extending across the spaces between said beams on 100 the inside thereof and arranged in horizontal and vertical rows, bolts securing the upper end of each plate to the beams, each plate having an inwardly offset marginal portion on one side and extending around one of the 105 lower corners of the plate, said offset portion overlapping the side of the adjacent plate and the adjacent upper corners of the plates immediately therebelow and covering the 110 bolts of said plates.

6. A wall, comprising a base member, upright beams secured to and supported by said base member, said beams being laterally spaced apart, a plurality of vertically arranged plates in each of the spaces between 115 the beams, said plates overlapping along their upper and lower edges and having their side margins overlapping the beams, and bolts securing the plates to said beams.

In testimony that I claim the foregoing 120 as my invention, I affix my signature, this 28th day of September, A. D. 1921.

ARTHUR P. STRONG.
